UNITED STATES PATENT OFFICE.

FRED J. MOSER, OF KANE, PENNSYLVANIA.

BAILER.

No. 896,566.

Specification of Letters Patent. Patented Aug. 18, 1908.

Application filed August 26, 1907. Serial No. 390,106.

To all whom it may concern:

Be it known that I, FRED J. MOSER, a citizen of the United States, residing at Kane, in the county of McKean and State of Pennsylvania, have invented new and useful Improvements in Bailers, of which the following is a specification.

This invention relates to bailers and consists in certain improvements in the construction thereof as will be hereinafter fully described and pointed out in the claims.

One of the objects of the invention is the improvement of the bailer tube itself.

Another object is providing means whereby the bailer tube may be filled regardless of the depth of mud in the well.

Other objects of the invention will appear from the specification and claims.

The invention is illustrated in the accompanying drawings as follows:

Figure 1 is a central longitudinal section of the device on the line 1—1 in Fig. 3. Fig. 2 is a section on the line 2—2 in Fig. 1. Fig. 3 is a side elevation of the lower end of the bailer tube. Fig. 4 is a section similar to that of Fig. 1 with the parts in a different position.

1 marks the bailer tube, cap 2 is secured to the tube 1 by means of a collar 3. The pin 4 extends through the opening 5 in the cap 2 and is provided with a head 6, and the screw threaded end 7 to which a cable or other means for raising or lowering the bailer may be attached. These are of ordinary construction.

The lower end of the bailer is formed of a tapered tube 8, which is connected to the tube 1 by a collar 9. The tapered tube has a discharge opening 10 at the side and a tapered sleeve 11 is arranged on the tube 8 and has an opening 12 that may be brought into register with the opening 10 to discharge the bailer. By making the lower part 8 of the tube tapered and the closure sleeve 11 similarly tapered a tight fit may be maintained, the

taper taking up the wear. The sleeve 11 is preferably free to move downwardly on the tube under the influence of gravity to maintain a close fit. The collar 9 forms a shoulder 14 which prevents the sleeve from sliding up on the tube 1.

The diaphragm 15 at the lower end of the tube has a passage 16 through it which is controlled by the clapper valve 17. I prefer

to make the diaphragm 15 approximately on a level with the opening 10 so that the mud is completely discharged from the tube 1 with each operation. This prevents the clogging of the valve.

To facilitate the mounting of the valve 17, I indent the walls of the side 8, at 18 forming a socket 19, the shank 20 of the valve extending into this socket is secured by the pivot pin 21. By indenting the walls of the tube, both the guide socket 19 is formed and a place for the heads of the pivot pin is provided so that the valve may be easily and securely mounted.

In the operation of bailers, as ordinarily constructed, the mud would be delivered directly from the well to the bailer tube through the clapper valve. In deep wells the small amount which can be raised with each operation makes the cleaning of a well a rather tedious matter. This is true even though a high level of mud is in the well. It is evident that as the level of mud recedes the load that can be lifted with an ordinary bailer diminishes. I have provided a means for obviating this difficulty which consists in providing a pump by means of which the mud is forced into the bailer and the bailer completely filled regardless of the level of mud in the well.

The tube 22 is screwed into the bottom of the end 8; it telescopes a tube 23 which forms the working barrel of a pump. A collar 24 is arranged on the end of tube 22 and a packing preferably rubber 25 is arranged immediately above the collar 24 and a collar 26 is arranged on the tube immediately above the packing. The collar 26 is adapted to engage the shoulder formed by the collar 27 at the end of the tube 23 so that the pump including the barrel 23 is lifted with the plunger tube 22, the plunger tube 22 having a limited telescopic movement relatively to the tube 23.

I prefer to make the end 28 of the collar 26 cone shape. The purpose of this is to force the packing 25 into engagement with the walls of the working barrel 23 as the plunger tube 22 is forced downward by the weight of the bailer above so that the mud in the working barrel is forced through the tube 22, past the clapper valve 17 into the bailer 1. It is evident that the heaviest

work of the plunger is in this forcing action so that a tighter joint is assured during the forcing stroke to the pump. It also takes up the wear in the packing so that a joint is effected even though the packing is much worn. The strainer 29 extends from the working barrel, being preferably formed of the same tube, and the diaphragm 31 is secured within the tube by means of collars 5 30 riveted to the tube. The diaphragm has the passage 32 through which the mud enters the working barrel. This passage is controlled by the check valve 33 which operates in the manner common to a working barrel in a pump. The bailer having been filled, it is drawn up and with the initial upward movement the plunger tube is drawn up in the working barrel, thus taking in a fresh charge of mud. This mud is objectionable, in that from its nature it is apt 10 to pack in the working barrel during the time the bailer is being raised and lowered so as to seriously interfere with the working of the device. To obviate this I attach a slotted link to the valve 33, and extend a pin 35 through the slot in the link 34. This pin is secured to the tube 22. With the normal operation of the pump the slotted link is of sufficient length to permit the valve 15 to operate in its normal manner but as the pump is raised carrying the plunger to its extreme position the pin 35 acts on the link 34 to lift the valve 33, as shown in Fig. 1, thus permitting the mud in the working barrel to escape.

The operation of the bailer is as follows: The apparatus is lowered into the well by means of the connection 7, the strainer 29 being preferably at the bottom of the well. 20 The connection 7 is then reciprocated carrying with it the bailer 2, and operating the tube 22 in the working barrel 23. The tube 22 operates and acts as a plunger. On the upward stroke mud and water is drawn into the working barrel, past the valve 33. On the downward stroke, the valve 33 is closed in a manner common to the lower valves in pumps and the charge is forced through the valve 17. The reciprocation of the plunger 25 is continued until the bailer is filled. The apparatus is then raised to the top of the well. The sleeve 11 is so turned as to uncover the discharge opening 10, so that the bailer tube may empty. As before stated the mud in the working barrel 23 is discharged with its initial upward movement by reason of the fact, that valve 33 is opened 30 by the action of the link 34 and pin 35.

What I claim as new is:

60 1. In a bailer for wells the combination of a bailer tube provided with a conico-cylindrical lower end, said lower end being provided with an opening through its bottom forming an intake for the tube and an open-

ing through its side for discharging liquid 65 from said bailer; a check valve controlling the opening forming the intake and a conico-cylindrical closure sleeve rotatively mounted on the said conico-cylindrical lower end and provided with an opening adapted to be 70 brought in register with the opening through the side of the lower conico-cylindrical lower end for opening and closing said lower end, the axial movement of the sleeve on the lower end being limited by the contact of the 75 conico-cylindrical surfaces on the interior of the sleeve and exterior of the lower end, whereby a close contact may be maintained as the surfaces wear.

2. In a bailer the combination of a bailer 80 tube having its lower end tapered and provided with a discharge opening and having a shoulder 14 arranged thereon; and a tapered closure sleeve arranged on the tube and adapted to close and open the discharge 85 opening as it is turned on the tube, said sleeve being locked on the tapered portion of the tube by said shoulder.

3. In a bailer the combination of a bailer tube having a discharge opening and indentations 90 18 arranged in the walls thereof; a valve secured between the walls formed by said indentations; and a closure sleeve arranged around the bailer tube, and adapted to open and close said discharge opening. 95

4. In a bailer the combination of a bailer tube having a discharge opening and a diaphragm approximately on the level of the opening; a valve arranged to operate on the diaphragm; and means for inclosing said 100 opening.

5. In a bailer the combination of a tube 1, having a tapered portion 8 secured thereto, said tapered portion having the opening 10 therein and indentations 18 in the walls 105 thereof forming the socket 19; the diaphragm 15 having the passage 16; a clapper valve 17 having an arm extending into the socket 19; a pivot pin extending through the arm and secured in the walls formed by said 110 indentations; the tapered sleeve 11 arranged over the sleeve 8 having the opening 12 adapted to be brought into register with the opening in the portion 8.

6. In a bailer the combination of a bailer 115 tube having a discharge opening from the side thereof; means for opening and closing the opening; a pump discharging into the tube; and means for raising and lowering the tube and operating the pump from the top of 120 a well.

7. In a bailer the combination of a bailer tube having a discharge opening from the side thereof; means for opening and closing the opening; a pump arranged below the 125 tube and connected therewith to discharge into the tube; and means for raising and lowering the tube from the top of a well.

8. In a bailer the combination of a bailer tube; a pump discharging into the tube, said pump having a plunger connected with said tube and arranged to be actuated by reciprocating said tube; and means for raising and lowering the tube. 65
9. In a bailer the combination of a bailer tube; a pump plunger secured to the bottom of said tube; a working barrel telescopically secured to the said plunger, said plunger being adapted to operate in the barrel as the inner tube is reciprocated and to lift the barrel as the bailer tube is lifted; and means for raising and lowering the bailer tube. 70
10. In a bailer the combination of a bailer tube having the discharge opening from the side thereof; means for opening and closing the same; the plunger tube 22 extending from the bailer tube; the working barrel 23 telescopically connected with said tube 22; a valve in the working barrel; and a valve between the pump and bailer tube. 75
11. In a bailer the combination of a bailer tube; having a plunger pump extending therefrom; the working barrel 23 telescopically connected with the plunger; the strainer 29 connected with the working barrel; a valve between the strainer and the working barrel; and a valve between the pump and the tube. 80
12. In a bailer the combination of a bailer tube; a pump connected with the bailer tube; a pump valve; and means for opening the pump valve for draining the pump as it is raised. 85
13. In a bailer the combination of a bailer tube; a pump connected with the bailer tube and adapted to discharge into said tube and to be raised and lowered into a well with said tube; and means for automatically draining said pump as it is raised. 90
14. In a bailer the combination of a bailer tube; a pump connected with the bailer tube and adapted to discharge into said tube and to be raised and lowered into a well with said tube; a pump valve; and means for automatically opening the pump valve as the pump is raised. 95
15. In a bailer the combination of a bailer tube; a plunger 22 extending therefrom; a working barrel; a valve 33 at the bottom of the working barrel; the slotted link 34 extending from the valve and secured to the plunger 22. 100
16. In a bailer the combination of a bailer tube; a working barrel; a plunger carried by the bailer tube and adapted to be reciprocated with the bailer; a packing 25 on said plunger; and a beveled shoulder adjacent to the packing, and adapted to engage said packing during the forcing stroke of the plunger. 105
17. In a bailer the combination of a bailer tube; a pump plunger 22 connected therewith, said plunger having a shoulder 24; packing 25; beveled collar 26; and the working barrel 23 operating on said plunger and having the collar 27 for engaging the collar 26. 110
18. In a bailer the combination of a bailer tube; a pump plunger 22 connected therewith, said plunger having a shoulder 24; packing 25; beveled collar 26; the working barrel 23 operating on said plunger and having the collar 27 for engaging the collar 26; the valve 33 at the bottom of the working barrel; means for telescopically connecting the plunger 22 and the valve 33, having a movement limited to lift the valve with the extreme movement of the plunger in the working barrel. 115
19. In a bailer, the combination of a bailer tube; a telescopic pump attached thereto and connected therewith for the purpose of mechanically filling said bailer tube, the pump being supported by the tube, whereby the pump may be lowered and raised from a well with the tube a valve between the tube and pump; and means for draining the tube above the valve. 120
20. In a bailer, the combination of a bailer tube; a telescopic pump attached thereto for the purpose of mechanically filling said bailer tube; and means for automatically draining said pump. 125
21. The combination of two tubes one of which telescopes within the other, and one extending above the other; means for preventing the separation of said tubes; devices attached to one of the tubes for lowering and lifting said tubes into and from a well and for reciprocating the tube to which the devices are attached with relation to the other tube; means for concentrically packing the space between them; a valve to prevent retrogression of liquid from said tubes while in operation; a valve between said tubes, the said combination forming a pump for mechanically filling a bailer tube in a well as specified herein; and means for draining the upper tube above the valve between the tubes. 130
22. The combination of two tubes one of which telescopes within the other; means for preventing separation of said tubes; means for concentrically packing the space between said tubes; a valve for preventing retrogression of liquid from said tubes while in operation and means for draining said tubes while removing them from the well; the said combination forming a pump for mechanically filling a bailer tube in a well as specified herein. 135
23. The combination of a conico-cylindrical member, of a bailer for wells provided with an opening through its bottom forming an intake and through its side forming a discharge; a check valve controlling the intake opening; and a conico-cylindrical closure sleeve fitted to said member and rotatively mounted thereon with an opening therein. 140

adapted to be brought into register with the opening in the side of the said member for the purpose described, the axial movement of the sleeve in one direction being limited by the contact of the surfaces on the interior of the sleeve with the exterior surface of the conico-cylindrical member, whereby the close fit is maintained as the surfaces wear.

In testimony whereof I have hereunto set my hand in the presence of two subscribing witnesses.

FRED J. MOSER.
